UNITED STATES PATENT OFFICE.

FERDINAND J. TILLMAN, OF ST. LOUIS, MISSOURI, ASSIGNOR TO TYPEWRITING CALCULATING ATTACHMENT COMPANY, OF ST. LOUIS, MISSOURI, A CORPORATION OF MISSOURI.

CALCULATING-MACHINE.

1,353,293. Specification of Letters Patent. Patented Sept. 21, 1920.

Application filed May 21, 1913, Serial No. 769,033. Renewed February 5, 1920. Serial No. 356,425.

To all whom it may concern:

Be it known that I, FERDINAND J. TILLMAN, a citizen of the United States of America, and a resident of the city of St. Louis and State of Missouri, have invented certain new and useful Improvements in Calculating-Machines, of which the following is a full, clear, and exact description, reference being had to the accompanying drawings, forming a part of this specification.

My invention relates to a calculating machine intended more particularly to be placed in operation by the numeral key levers of a type writing machine, the invention pertaining, more especially, to multiplying mechanism.

Figure I is a top or plan view of my machine, the casing being partly broken away, and certain members being shown in horizontal section, on line I—I, Fig. II.

Fig. II is a vertical longitudinal section taken on irregular line II—II, Fig. I.

Fig. III is an elevation of the mechanism for shifting the gear wheel on the transmission shaft leading to the registering mechanism.

Fig. IV is an enlarged view, partly in elevation and partly in vertical section, of the locking device associated with the shaft by which the registering mechanism carriage is shifted.

Fig. V is a vertical longitudinal section taken on line V—V, Fig. I.

Fig. VI is an enlarged top or plan view of the clutch device associated with the multiplying wheel shaft.

Fig. VII is an enlarged front elevation of the clutch device shown in Fig. VI.

Fig. VIII is an enlarged top or plan view of a fragment of the transmission shaft.

Fig. IX is an enlarged elevation of the parts shown in Fig. VIII.

My calculating machine being one intended, more particularly, to be placed in operation through the medium of the numeral key levers of a typewriting machine I will, without limiting myself to any particular means for rendering it operative, describe the machine as operated by the numeral key levers of any ordinary typewriting machine, as contemplated in my U. S. Patent No. 933,600, issued September 7, 1909.

With this understanding I will first state that A designates the numeral key levers of a typewriting machine which is intended to be placed above my calculating machine, these key levers being provided with keys B and being of denominations from one to nine.

1 designates the base of my calculating machine surmounted by side members 2, which, with said base, form the frame of my machine. The frame thus formed preferably has attached to it a top housing 3 by which an inclosure for the calculating mechanism is completed.

4 designates a transverse rod mounted in the side frame members 2. 5 are integer wheels loosely arranged on said rod, there being nine of these wheels responding to the numeral key levers A. The integer wheels 5 are provided with peripheral teeth that are adapted to be placed in mesh with wheels on a constantly rotating shaft, whereby said wheels will have partial rotation imparted to them in different degrees, each integer wheel being rotated a distance that causes it to impart to the transmission shaft a movement that is the equivalent of a series of steps corresponding in number to the numerical value of the integer wheels.

6 designates the drive shaft and 7 the wheels fixed thereto to which the peripheral teeth of the integer wheels are moved, in order that the integer wheels may be partially rotated during engagement between their peripheral teeth and the drive wheels. 9 is a transmission shaft parallel with the integer wheel supporting rod 4 and the drive shaft 6 and on which are rigidly mounted a series of transmission wheels 8. All of the transmission wheels 8 are operable by the integer wheels to a degree corresponding to that to which said integer wheels are operated by the wheels on the drive shaft 6. The operation of the transmission shaft by the integer wheels is in conformity to the degree of operation of each integer wheel during engagement of its peripheral teeth.

The transmission shaft 9 is provided with a miter wheel 10 that meshes with a miter wheel 11 on a transmission shaft 12 leading to registering mechanism. The parts just described are quite similar, in general, to

corresponding parts in my patent before mentioned, and reference may be had to said patent for a more complete understanding of the operation of said parts, and of a suitable connection between the registering mechanism and transmission shaft operable by the integer wheels.

13 designates a transverse rod supported in front of the series of integer wheels 5, 10 this rod serving as a support for certain parts including a frame comprising side arms 14 pivoted to said rod, a rod 15 connecting the ends of the arms, and a rod 16 mounted in the arms 14 between the rods 15 and 13. The frame comprising the members just mentioned is normally held in lowered position by one or more springs 17, (see Figs. II and V), connecting said frame to the base or other stationary part of the 20 machine.

18 designates dogs loosely mounted on the transverse rod 13, the number of these dogs being similar to the number of the integer wheels, the dogs being provided with rearwardly extending arms 19, which lie in the path of travel of stop pins 5', projecting from the sides of the integer wheels, the engagement of said parts providing for the integer wheels being normally held from rotation. The dogs 18 are provided with forwardly extending tail arms 21, which lie beneath the transverse rod 15 carried by the arms 14, pivoted to the rod 13. The function of these tail arms will be hereinafter set forth. 23 are gravitational detents, loosely arranged on the rod 13 alongside the dogs 18, and normally upheld by lips on the detents resting upon the rear arms of said dogs, so that while the stop pins of the integer wheels are normally in abutment against the arms of the dogs, the rear ends of said gravitational detents lie above said stop pins; but when the rear arms of the dogs are lowered to permit passage of the stop pins 45 over the lips of said arms, the stop pins ride beneath the gravitational detents, after which the latter move downwardly and occupy positions that will cause the next succeeding stop pins on the integer wheels to come into engagement with the detents, pending the return of the dogs 18 to their normal positions.

The means utilized in the present machine for imparting initial partial rotation to the integer wheels 5 may be advantageously set forth at this point in the description. 55 25 are cam levers arranged in series upon a transverse rod 26 situated in front of the integer wheels 5. These cam levers are 60 loosely mounted on the rod 26 and each cam lever is provided at its rear end with a downwardly and rearwardly inclined cam 27, the top of each cam lever being formed with an apex point 28 at which the cam face 65 27 terminates. The several cam levers 25,

one for each individual integer wheel, are normally held by pull springs 29, connecting their forward arms 30 to the frame of the machine, so as to hold the cam faces 27 at the rear ends of the cam levers against 70 stop pins 5' on the integer wheels. The pull springs 29 are constantly under tension, but upward movement of the cam levers thereby cannot take place as long as rotation of the integer wheels is prevented by 75 the dogs 18 in engagement with stop pins 5'. When, however, a dog 18 is moved to free the stop pin previously engaged by it, the cam lever 25 corresponding in position to said dog is permitted to come into action 80 to impart initial rotation to the released integer wheel. The pull springs 29 of the proper cam lever then act to move the cam lever 25 upwardly, and, as a result, the cam 27, by riding against the stop pin of the 85 integer wheel in engagement with it, occasions sufficient rotation of the integer wheel to cause a peripheral tooth thereon to be brought into engagement with a wheel 7 on the drive shaft 6, following which the integer wheel is operated by said shaft to a degree corresponding to the integer represented by the integer wheel. Such movement is communicated from the integer wheel to the transmission shaft 9 and therefrom to the 90 registering mechanism of the machine.

The mechanism for operating the dogs 18 that control the rotation of the integer wheels 5 will next be described. This mechanism is operable by the numeral key levers 100 A and comprises a series of levers 32 located beneath said key levers and loosely mounted upon a pivot rod 33. The arms of the levers 32 which are engaged by the key levers A are maintained in normal positions 105 by springs 34, (see Fig. II), and said levers are provided with tails 32' connected by pull rods 35 to the dogs 18. When a numeral key lever A is depressed, the lever 32 beneath it is operated, and the pull rod 35 110 attached to said lever is drawn forwardly, whereby the dog operable by said lever is operated to free the integer wheel normally restrained thereby, and said integer wheel is brought into action in the manner set 115 forth.

The parts of my machine thus far described are such as may be used in calculations involving addition and subtraction, and no invention is herein claimed for them 120 *per se*.

36 designates a multiplying wheel shaft in front of the transmission shaft 9. This shaft 36 has fixed to it a series of multiplying wheels 37, having teeth of varying numbers, 125 suitable for multiplication of the integers 2, 3, 4, 5, 6, 7, 8 and 9. The shaft 36 is driven by a drive wheel 38 on the transmission shaft 9, which meshes with a pinion 39 loosely mounted on said shaft 36, and it will 130

be understood that said pinion is driven whenever the transmission shaft 9 is rotated by the integer wheels 5.

When my machine is in service for other than multiplying, the pinion 39 turns idly on the multiplying shaft and it is brought into operation to operate said shaft by clutch mechanism, comprising the following parts: 41, (see Figs. I, VI and VII), is a clutch sleeve splined to the multiplying shaft adjacent the pinion 39, and provided with teeth 42, which may be moved into mesh with clutch teeth 40 on the side of the pinion 39. The clutch sleeve 41 is provided with an annular groove 43 which receives the fork of a shifter arm 44 pivoted to the base of a post 45 in which the multiplying shaft 36 is journaled. A retracting spring 46 (see Figs. VI and VII), connecting the shifter arm to the post 45, serves to hold the clutch sleeve 41 normally separated from the clutch teeth of the pinion 39, and the clutch sleeve is shifted to engage said pinion by a bell crank lever 47, the said lever having one of its arms fitted to a rotatable cam 48 mounted on a horizontal support 49, extending from the post 46 beneath the multiplying shaft. By movement of the bell crank lever 47, the cam 48 works against the shifter arm 44, and causes it to carry the clutch sleeve 41 into co-operative engagement with the pinion 39, thereby providing for the rotation of the multiplying shaft with said pinion. The bell crank lever 47 is operated by a connecting rod 50 extending from said lever to mechanism for imparting longitudinal movement thereto, as will be herein-after described.

51 designates the transmission shaft of the multiplying mechanism, (see Figs. I, II, V, VIII and IX), operable by any of the multiplying wheels 37 through the medium of transmission wheels 52 movable into and out of engagement with the multiplying wheels. Each transmission wheel 52 is loosely mounted on the shaft 51 and is provided with a clutch member 53, which is shiftable to and from an adjacent clutch member 54 fixed to said shaft. Beneath the transmission shaft 51 of the multiplying mechanism is a frame member 55, secured to the base 1, including posts 56 which are located in proximity to the several transmission wheels 52. 57 are shifter arms pivoted to the frame member 55, and having forks which are fitted in grooves in sleeves 52' carried by the multiplying mechanism transmission wheels 52. These shifter arms serve to move the clutch members 53 of the transmission wheels 52 into and out of engagement with the clutch members 54 fixed to the multiplying mechanism transmission shaft. Desired movements of the shifter arms 57 are secured by toggles 58, each having one link pivoted to the sleeve of the transmission wheel 52 shift-

able thereby, and its other link pivoted to the adjacent post 56. Toggle operating rods 59 lead from said toggles to mechanism which will be subsequently set forth.

The multiplying mechanism transmission shaft 51 has fixed to it at its end nearest the transmission shaft 12, leading to the registering mechanism, a gear wheel 60, which is constantly in mesh with a gear wheel 61, fixed to a short shaft 62, carrying also a bevel gear 63, meshing with a bevel gear fixed to the shaft 12. Consequently, any rotative movement imparted to the transmission shaft 51 of the multiplying mechanism by the multiplying wheels 37 is communicated to the transmission shaft 12.

The registering mechanism operable by the transmission shaft 12 comprises total wheels 64 meshing with gear wheels 65, and a traveling drive wheel 66 splined to a drive shaft 67, the traveling wheel 66 being adapted to mesh with any of the gear wheels 65. The drive shaft 67 is provided with a bevel gear 68, (Fig. I), meshing with a bevel gear 69 on the transmission shaft 12. The traveling drive wheel 66 turns with the drive shaft 67, and said wheel travels on the drive shaft step by step, as will be hereinafter more particularly set forth.

The multiplying keys M, (Figs. I and II), are operable to shift the clutch sleeve 41, on the multiplying wheel shaft 36, into engagement with the clutch teeth on the pinion 39, at the same time shifting one of the pinions 52 so that its clutch teeth will interlock with a clutch member 54 on the transmission shaft 51, also disengaging the miter wheel 11, on the transmission shaft 12, from the miter wheel 10 on the shaft 9. I will now describe the key connections for shifting the different clutch members. Each multiplying key M is secured to a bell crank lever 70 supported by a pivot rod 71. A series of lever arms 72 supported by a pivot rod 73 are secured at their upper ends to the several bell crank levers 70.

74 designates restoring springs connecting the lever arms 72 to a stationary cross bar 75. The toggle operating rods 59 connect the toggles 58 to the lever arms 72, so that any one of the multiplying keys M may be operated to shift one of the shifter arms 57, thereby moving one of the clutch members 53 into engagement with a clutch member 54 fixed to the shaft 51. This operation will cause the shaft 51 of the multiplying mechanism to turn in response to movements of the multiplying wheel shaft 36.

The means for disengaging the miter wheel 11 from the miter wheel 10, and at the same time engaging the clutch member 41 with the clutch teeth on the drive pinion 39, comprises an abutment rod 76 engaging the several key levers 70 and connected at its ends to arms 77, the latter being pivotally connected to the frame member 55.

supported by a rod 78. One of the arms 77 is connected to a pull rod 79, (Figs. I and III), which may be operated to shift the miter wheel 11 as will be presently described, and the other arm 77 is connected to the pull rod 50, (Fig. I), located at the right hand side of the machine, and connected to the cam operating lever 47. When the pull rod 50 is pulled toward the front 10 of the machine, the bell crank lever 47 is rocked, with the result of rocking the cam 48 and shifter arm 44 to shift the teeth of the clutch sleeve 41 into engagement with the clutch teeth on the pinion 49. This causes 15 the multiplying wheel shaft 36 to turn in response to movements of the drive wheel 38 on the transmission shaft 9. The miter wheel 10 on the end of the transmission shaft 9 is disengaged from the miter wheel 20 11 by the following mechanism, (see Figs. I, II, and III):

80 designates a shifter arm secured to a rock shaft 81 and provided with a bifurcated upper end which lies in an annular 25 groove in the miter wheel 11. A rocker arm 82, secured to the inner end of the rock shaft 81, is formed with a slotted end to receive a pin at the end of a bell crank lever 83. The bell crank lever 83 is pivoted at 30 84 and provided with a short arm 85, to which the pull rod 79 is connected.

86 designates a restoring spring (Fig. III), tending to shift the miter wheel 11 into engagement with the miter wheel 10.

35 When one of the multiplying keys M is depressed, its bell crank lever 70 is rocked to shift the abutment rod 76 toward the rear of the machine. The arms 77, at the ends of the abutment rod 76, are then rocked 40 on the pivot rod 78 so that the pull rods 79 and 50, secured to the arms 77, are pulled forwardly. The pull rod 79 operates the parts shown in Fig. III so as to disengage the miter wheel 11 from the miter wheel 45 on the shaft 9, while the pull rod 50 at the right hand side of the machine moves the cam operating lever 47 to shift the clutch sleeve 41, as previously described. This operation causes the movements of the integer 50 wheels 5 to be transmitted to the registering mechanism through the following parts: One of the wheels 8 meshing with one of the integer wheels 5, transmission shaft 9, drive gear 38, pinion 39, clutch sleeve 41, 55 multiplying wheel shaft 36, one of the multiplying wheels 37, one of the pinions 52, one of the clutch members 54, shaft 51, bevel gear 60 at the end of said shaft, bevel gear 61, short shaft 62, miter wheel 63, transmission shaft 12, miter gears 69 and 68, and the drive shaft 67 to which the traveling drive wheel 66 is splined.

In performing addition the parts of the machine occupy the positions seen in Fig. I, 60 the miter gears 10 and 11 being engaged

with each other so that the movements of the integer wheels 5 are transmitted to said miter wheels through the transmission wheels 8, (Fig. II), and transmission shaft 9, the miter wheel 10 being secured to the shaft 9. 70

In performing calculations involving multiplication, the desired multiplying key M is depressed to throw the clutch mechanism, previously described, and the selected multiplying key is held down by a latch rod 90 75 carried by spring actuated arms 91 pivoted to a rod 92, see Figs. I and II. One of the numerals keys B is then depressed to release one of the integer wheels 5, thereby permitting said integer wheel to be turned a certain number of steps by one of the constantly rotating drive wheels 7, (Figs. II and V). The motion of the integer wheel is then transmitted to the registering mechanism through the long train of gearing, including one of the multiplying wheels 37 80 and one of the pinions 52. The motion of the integer wheel is multiplied through the medium of the multiplying wheels 37 and 52, and the registering mechanism is driven to 85 indicate the product of the multiplier and multiplicand represented by the two selected keys. For example, depressing the "4" key of the group B will cause the "4" integer wheel to move four steps; and if the "5" key of group M has been depressed, one 90 of the multiplying pinions 52 will be interlocked with a clutch member 54, so that the movement of the pinion 52 selected by the "5" key will be 5×4 steps. The transmission shafts 51 and 12 will then move 20 steps 95 and advance the registering mechanism accordingly.

The traveling drive wheel 66 of the registering mechanism is stepped along the drive 100 shaft 67 in unison with the movements of the paper carriage of the typewriting machine, the movements of the paper carriage being transmitted to the traveling drive wheel by mechanism quite similar to that 105 shown in my Patent No. 933,600. I will therefore only briefly describe this mechanism. The traveling drive wheel 66 is rotatably fitted to a traveling carriage in the form of a feed arm 95 splined to a feed 110 shaft 96, said feed shaft having spiral grooves for the reception of lugs or pins on the feed arms 95. 97 is a bevel gear fitted to one end of the feed shaft 96, and meshing with a bevel gear 98 on a shaft 99 115 which extends to the rear end of the machine. The paper carriage, see Fig. I, includes a platen 100 and a rack bar 101, the latter being in mesh with a pinion 102 at the upper end of a vertical shaft 103. A bevel gear 104 fixed to the lower end of shaft 103 meshes with a pinion 105 on the rear end of the shaft 99. It will be noted that a longitudinal movement of the paper carriage C 120 will rotate the vertical shaft 103, horizontal 125

shaft 99, and the spirally grooved feed shaft 96, thereby stepping the traveling drive wheel 67 to the registering wheels of different orders.

5 The rotary movement of the traveling drive wheel 66 must be completed before the said drive wheel steps away from the registering wheel in which the sum or product is to be recorded. I therefore provide means 10 for restraining the traveling wheel and paper carriage during the operation of the calculating mechanism, said traveling wheel and carriage being released automatically at the end of each calculating operation. 106 15 is a toothed wheel fixed to the obliquely arranged shaft 99, and 107 is a locking dog adapted to move between the teeth of said wheel. The locking dog is pivotally supported at 108, (Fig. IV), and its rear end is 20 connected to the rod 15 by means of a link 109. A spring 110, (Fig. IV), tends to pull the locking dog away from the toothed wheel 106. A detent 111, arranged below the locking dog, is pivoted at 112, and provided with a tail 113, which overlies a rockable plate 114, the latter being pivoted to a rod 115. The rockable plate 114 extends transversely of the machine and its free edge overlies the tails of the cam levers 25. As 25 previously described, when one of the type-writing machine keys B is depressed, one of the dogs 18, (Fig. II), is rocked so that its arm 21 moves upwardly. This raises the transverse rod 15, and at the same time begins the calculating operation by releasing an integer wheel 5. The transverse rod 15 being connected to the locking dog 107 by the link 109, an upward movement of rod 15 acts to move said locking dog between two of the teeth on the wheel 106, thus locking the shaft 99. When the locking dog 107 rocks into engagement with the wheel 106, the spring actuated detent 111, (Fig. IV), rides under a nose 117 on the locking 40 dog 107, thereby holding said dog engaged with the wheel 106. At the end of the calculating operation one of the pins 5' carried by an integer wheel 5 rides over the apex 45 28 of a cam lever 25, and the cam lever is thus moved to elevate the free edge of the rockable plate 114. This action moves the detent 111 to the position seen in Fig. IV, and the spring 110 then pulls the locking dog 107 away from the toothed wheel 106. 50 55 It will be understood that the mechanism just described locks the shaft 99 to prevent the traveling wheel 66 and paper carriage C from traveling while said wheel is driving one of the register wheels, and thereafter automatically releases the traveling members to permit the desired traveling movement.

I claim:

1. In a calculating machine, multiplying mechanism and registering mechanism oper-

able by said multiplying mechanism, the said multiplying mechanism including a multiplying shaft provided with a series of multiplying wheels, a transmission shaft, a series of pinions loosely mounted on said transmission shaft adapted to be driven by said multiplying wheels, a series of clutch members, multiplying keys, and means operable by said multiplying keys for engaging any one of said pinions with one of said clutch members. 70 75

2. In a calculating machine, multiplying mechanism and registering mechanism operable by said multiplying mechanism, the said multiplying mechanism including a multiplying shaft provided with a series of multiplying wheels, a transmission shaft, a series of pinions loosely mounted on said transmission shaft adapted to be driven by said multiplying wheels, a series of clutch 80 85 members on said transmission shaft, multiplying keys, and means operable by said multiplying keys for engaging any one of said pinions with one of said clutch members. 90

3. In a calculating machine, registering mechanism, a power shaft, and means for transmitting the movement of said power shaft to said registering mechanism; said means including multiplying wheels having different numbers of teeth, a drive clutch for transmitting the movements of said power shaft to said multiplying wheels, a series of clutch members for transmitting the individual movements of said multiplying wheels, numeral keys, and clutch shifting devices operable by said numeral keys to shift said drive clutch and any one of said series of clutch members. 95 100

4. In a calculating machine, registering mechanism, a driving member, and means for transmitting the movement of said driving member to said registering mechanism; said means including multiplying wheels having different numbers of teeth, a drive clutch for transmitting the movements of said driving member to said multiplying wheels, a series of clutch members for transmitting the individual movements of said multiplying wheels, numeral keys, and clutch shifting devices operable by said numeral keys to shift said drive clutch and any one of said series of clutch members. 105 110 115

5. In a calculating machine, registering mechanism, a power shaft, integer wheels operable by said power shaft, a transmission shaft associated with said registering mechanism, a shiftable toothed member for transmitting the movements of said integer wheels to said transmission shaft, multiplying keys, means, under the control of said multiplying keys, for shifting said shiftable toothed member, multiplying mechanism, clutches for causing the movements of said integer wheels to be transmitted 120 125 130

- through said multiplying mechanism to said transmission shaft, and means, under the control of said multiplying keys, for shifting said clutches.
5. 6. In a calculating machine, calculating mechanism including numeral keys, registering mechanism provided with a rotatable drive shaft and a drive wheel splined to said drive shaft, means for sliding said 70 drive wheel along said drive shaft, said means including a rotatable shaft provided with a toothed wheel, a locking dog movable into engagement with said toothed wheel, means for shifting said locking dog 75 into engagement with said toothed wheel, and means, operable by the calculating mechanism, for releasing said locking dog from said toothed wheel.
10. 7. In a calculating machine, calculating mechanism including numeral keys, registering mechanism provided with a rotatable drive shaft and a drive wheel splined to said drive shaft, means for sliding said drive wheel along said drive shaft, said means including a rotatable shaft provided with a 80 toothed wheel, a locking dog movable into engagement with said toothed wheel, means under control of the numeral keys for shifting said locking dog into engagement with 85 said toothed wheel, and means, operable by the calculating mechanism, for releasing said locking dog from said toothed wheel.
15. 8. In a calculating machine, multiplying mechanism and registering mechanism operable by said multiplying mechanism, the 90 said multiplying mechanism including a multiplying shaft provided with a series of multiplying wheels, a transmission shaft, a series of pinions loosely mounted on said 95 transmission shaft adapted to be driven by said multiplying wheels, a series of clutch members, and means for engaging any one of said pinions with one of said clutch members.
20. 9. In a calculating machine, multiplying mechanism and registering mechanism operable by said multiplying mechanism, the 100 said multiplying mechanism including a multiplying shaft provided with a series of multiplying wheels, a transmission shaft, a series of pinions loosely mounted on said transmission shaft adapted to be driven by said multiplying wheels, a series of clutch members on said transmission shaft, and means for engaging any one of said pinions with one of said clutch members.
25. 10. In a calculating machine, registering mechanism, a power shaft, and means for transmitting the movement of said power 105 shaft to said registering mechanism; said means including multiplying wheels having different numbers of teeth, a drive clutch for transmitting the movements of said power shaft to said multiplying wheels, a series of 110 clutch members for transmitting the individual movements of said multiplying wheels, and clutch shifting devices operable to shift said drive clutch and any one of said series of clutch members.
30. 11. In a calculating machine, registering 70 mechanism, a driving member; and means for transmitting the movement of said driving member to said registering mechanism; said means including multiplying wheels having different numbers of teeth, a 75 drive clutch for transmitting the movements of said driving member to said multiplying mechanism, a series of clutch members for transmitting the individual movements of 80 said multiplying wheels, and clutch shifting devices operable to shift said drive clutch and any one of said series of clutch members.
35. 12. In a calculating machine, registering 85 mechanism, a power shaft, integer wheels 90 operable by said power shaft, a transmission shaft associated with said registering mechanism, a shiftable toothed member for transmitting the movements of said integer wheels to said transmission shaft, multiplying means including keys, and under the control of said keys, for shifting said shiftable toothed member, multiplying wheels having different numbers of teeth, clutches for causing the movements of said integer 95 wheels to be transmitted through said multiplying wheels to said transmission shaft, and means for shifting said clutches.
40. 13. In a calculating machine, calculating 100 mechanism including numeral keys, registering mechanism provided with a rotatable drive shaft and a drive wheel splined to said drive shaft, means for sliding said drive wheel along said drive shaft, said means including a rotatable shaft provided with a 105 toothed wheel, a locking dog movable into engagement with said toothed wheel, means for shifting said locking dog into engagement with said toothed wheel, and means for releasing said locking dog from said 110 toothed wheel.
45. 14. In a calculating machine, calculating mechanism including numeral keys, registering mechanism provided with a rotatable drive shaft and a drive wheel splined to said drive shaft, means for sliding said drive wheel along said drive shaft, said means including a rotatable shaft provided with a toothed wheel, a locking dog movable into engagement with said toothed wheel, means under control of the numeral keys for shifting said locking dog into engagement with said toothed wheel, and means for releasing said locking dog from said 115 toothed wheel.
